[57] **CLAIM**

The ornamental design for a combined hand held keyboard and hand strap therefor, as shown and described.

DESCRIPTION

FIG. 1 is a top front and side perspective view of a combined hand held keyboard and hand strap therefor showing our new design;

FIG. 2 is a back perspective view thereof;

FIG. 3 is a front elevational view thereof with the strap omitted;

FIG. 4 is a side elevational view thereof opposite that shown in FIG. 1;

FIG. 5 is a back elevational view thereof;

FIG. 6 is a top plan view thereof; and,

FIG. 7 is a bottom plan view thereof.
